UNITED STATES PATENT OFFICE.

JASON A. LODWICK, OF PELHAM MANOR, NEW YORK, ASSIGNOR TO AMERICAN ARCH COMPANY, A CORPORATION OF DELAWARE.

FURNACE STRUCTURE.

Application filed August 30, 1922. Serial No. 585,147.

This invention relates to furnace structures and more particularly to the arch, nose and curtain brick of the combustion chamber, and means for supporting the same.

One of the primary objects of my invention is the provision of an improved means of supporting the nose of the arch so that the nose will automatically align itself with the arch; that is to say, accommodate itself to the angular disposition of the arch, in which connection the arches are sometimes disposed substantially horizontally and at other times at varying angles.

15 Another object of the invention is to provide a support having the characteristics described, and by means of which the nose, considered as a whole, is supported independently of the arch, and by means of 20 which, also, the bricks constituting the nose are also independently supported so that one or more units thereof may be removed without disturbing the remaining bricks of the nose.

25 Still another object of my invention is the provision of a combined curtain and nose brick supporting means whereby the curtain and nose brick are supported independently of one another and the nose brick are permitted to accommodate themselves to the arch.

30 The foregoing, together with such other objects as may hereafter appear or are incident to my invention I obtain by means of 35 a construction the preferred embodiments of which are shown in the accompanying drawings, wherein

Figure 1 is a cross-section through a stoker-fired furnace, illustrating my improvements;

40 Figure 2 is an enlarged section showing the curtain and nose brick and the means for supporting the same and also the end course of the main arch; and

45 Figure 3 is a section taken on the line 3-3 of Figure 2.

Referring now to Figure 1, the reference letter A designates the main arch which comprises the courses of bricks a, b, c, d, 50 and e, the bricks of the courses a, c and e being shouldered and provided with heads and being suspended by means of hangers 7 from beams 8 of the furnace structural work. The courses b and d are supported 55 from the bricks of the courses a, c and e.

The nose is indicated as a whole by the reference letter B. The nose is composed of a plurality of bricks 9, such bricks being shaped so that when they are assembled in pairs a head 10 is provided at the inner upper corners, the heads being adapted to be engaged by clip members 11, which are pivotally connected to the T-shaped members 12. These T-shaped members have their heads 12^a slightly rounded and such heads 60 are adapted to fit in a key hole slot or opening 13 formed in the supporting member 14. The supporting members 14 are secured to the transverse L beam 15, of the supporting structure of the furnace, preferably detachably, as by means of the hook or nose 65 16, which is adapted to be slipped over the flange at the lower edge or base of the beam.

By virtue of this arrangement the bricks 70 of the nose can swing about the pivot bolts 75 11^a by which the clips 11 are pivoted to the T-shaped members 12 and thus automatically accommodate themselves to the main arch B. This arch, as heretofore pointed out, is sometimes horizontally disposed and at other times at various angles of inclination, but the pivotal support of the nose brick will always insure that the nose is brought into alignment with the main arch. The pivotal support of the clips and the 75 more or less pivotal engagement of the T-shaped members 12 in the key-hole slots affords a suspension for the bricks which provides substantially universal motion so that the bricks of the nose will not only 80 accommodate themselves to the arch but may swing laterally somewhat.

The laterally projecting supporting member 14 is provided with T-shaped head 17 at its outer end, affording pivotal support 85 for the curtain bricks 18 of the curtain wall C. The curtain brick 18 is provided with a recess or aperture 19 so that it may be hooked over the T heads 17. From an inspection of Figure 3 it will be seen that a pair of the bricks 18 is supported on each 90 T head 17. Thus the curtain bricks 18 and the nose brick 9 are supported and articulated independently of one another (and of the arch) on combined supporting means 95 so that either the curtain brick or the nose brick may be removed for purposes of replacement without disturbing the other bricks, and damaged nose brick or damaged curtain brick can be removed without dis- 100

turbing the remaining nose brick or curtain brick.

The gap between the main portion of the curtain wall C, resting on the cross beam 16 and the curtain bricks 18 in front of said beam 15 is closed by one or more rows of curtain bricks 20. To remove one or more of the curtain bricks 18 the joint between the bricks 18 and the respective bricks 20 is cracked and the latter are removed, which affords opportunity for slipping off the damaged bricks 18 from their supporting heads 17.

The supporting means is protected from the heat and is accessible from the front, and the arrangement in addition to having the advantages heretofore noted is such that the bricks may be readily installed. Other advantages will occur to those skilled in the art.

I claim:

1. A construction of the character described comprising an arch, a nose supported independently and automatically self-accommodating to the angular arrangement of the arch, and curtain brick supported independently of the nose but automatically self-accommodating thereto.

2. A construction of the character described comprising an arch, a nose, a superjacent refractory curtain brick, said nose and said curtain brick being independently articulated for self-adjustment lengthwise of the furnace.

3. A furnace arch construction of the character described comprising, in combination with the supporting structure of the furnace, a supporting member carried thereby, a nose brick pivotally supported from said member, and a curtain brick also pivotally supported from said member.

4. A furnace arch construction of the character described comprising, in combination with a cross-beam of the furnace, a laterally projecting supporting member mounted on its lower edge, a nose brick suspended from said member, and a curtain brick resting on said member in front of the cross-beam.

5. A furnace arch construction of the character described comprising, in combination with a cross-beam of the furnace, a laterally projecting supporting member mounted on its lower edge, a curtain brick pivoted on the outer end of said member,

and a nose brick pivotally suspended from said member.

6. A furnace arch construction of the character described comprising, in combination with a cross-beam of the furnace flanged at its lower edge, a laterally projecting supporting member detachably engaged with the flange, a curtain brick resting on said member in front of the cross-beam, a nose brick, and a hanger for the nose brick normally engaging said member, but detachable by movement lengthwise of the beam.

7. A furnace arch construction of the character described comprising, in combination with a cross-beam of the furnace, a supporting member carried thereby, a nose brick suspended from said member, a curtain brick resting on said supporting member in front of said cross-beam, a curtain wall resting on said cross-beam, and refractory brick in front of said beam between said curtain brick and said curtain wall.

8. In furnace structures, an arch nose brick supporting means including a member adapted to be attached to structural work of the furnace, a member detachably carried thereby, and brick engaging means pivotally secured to said second member, said first member being provided with means for supporting curtain brick.

9. In furnace structures, an arch nose brick supporting means including a member adapted to be attached to structural work of the furnace, a member detachably carried thereby, and brick engaging means pivotally secured to said second member, one of said members being adapted to support curtain brick.

10. In furnace structures, a combined curtain and nose brick supporting member, adapted to support the curtain and nose brick independently the one of the other and the nose brick pivotally.

11. In furnace structures, an arch nose brick support including a beam, a member detachably carried thereby and provided with a keyhole slot, a T-shaped member fitting said slot, and brick engaging means secured to said T-shaped member.

In testimony whereof I have hereunto signed my name.

JASON A. LODWICK.
